United States Patent

Des. 236,327
Patented Aug. 19, 1975

236,327

CLOCK OR SIMILAR ARTICLE

Morris W. Wilson, Fairfield, Conn., assignor to
General Electric Company

Filed Nov. 9, 1973, Ser. No. 414,368

Term of patent 7 years

Int. Cl. D10—01

U.S. Cl. D10—23

FIG. 1

FIG. 2.

FIG. 3.

FIG. 4.

FIG. 5.

FIG. 1 is a front perspective view of a clock showing my new design;

FIG. 2 is a right side elevational view thereof, the left side being a mirror image thereto;

FIG. 3 is a front elevational view thereof;

FIG. 4 is a rear elevational view thereof; and

FIG. 5 is a top plan view thereof.

I claim:

The ornamental design for a clock or similar article, as shown and described.
